FORGING RAM AND ROD CONNECTION

Samuel B. Heppenstall, Pittsburgh, Pa., assignor
to Heppenstall Company, Pittsburgh, Pa., a cor-
poration of Pennsylvania

Application May 11, 1931, Serial No. 536,485

7 Claims. (Cl. 287—20)

This invention relates to forging hammers and has particularly to do with the connections of the piston rods to the rams or heads of such hammers.

5 In the operation of hammers of this character it frequently happens that the piston rods on which the rams are mounted break and have to be replaced a number of times before the rams are worn out or destroyed. The making of these re-
10 placements in the past has been a very difficult and tedious task because as a rule the rods usually become very rigidly locked in the rams due to the heavy hammering to which they are subject-
15 ed in service. In fact they are often practically welded in the heads as a result of the tremendous pressures encountered and have to be removed by drilling or boring them out and this not infre-
quently ruins the rams.

With these difficulties in mind it is an object
20 of this invention to provide a hammer ram and piston rod connection which is adapted to meet all the requirements of such a connection and at the same time is adapted to permit the rod being removed from the ram without injury
25 thereto and with relative ease when necessitated.

Another object is to provide a connection embodying the aforementioned characteristics which is simple and relatively inexpensive to manufacture and both efficient and durable in
30 service.

These and various other objects, as well as the various other novel features and advantages of the invention, will be apparent when the following detailed description is read in con-
35 junction with the accompanying drawing, of which Figs. 1 and 2 are vertical sectional views of two piston rod and ram connections embodying the invention, but in which the thickness of the metal coatings applied to the contacting surfaces
40 of the connecting rods and heads is somewhat ex-
aggerated.

The invention is predicated upon my discovery that by applying a very thin coating or layer of some suitable dissimilar metal, and preferably a
45 soft metal such as copper or the like, over the surface of either the rod or the bore in the ram or head of a forging hammer where these parts engage each other, and by applying it to one or the other of these surfaces in such a way that it will not be readily crumpled and destroyed or displaced when the rod is mounted in the ram, a very excellent connection is provided and at the same time it adapts the rod to be removed from the ram with ease and without subjecting
50 the head to injury.

It is my belief that such a coating functions both as a sort of lubricant and as a surfacing medium which flows sufficiently to fill up the small or microscopic pores or irregularities which occur in the engaging surfaces of the rod and ram and thereby prevents them from becoming welded together or from interlocking or gripping each other in such a way that they can not be readily separated when necessary.

Referring to the embodiment of the invention
60 illustrated in Fig. 1, the numeral 1 designates a conventional form of forging hammer ram in which there is provided a central bore 2 for the reception of the lower end of a piston rod 3 to which the ram is attached for reciprocation
65 in the customary fashion through the use of a suitable fluid pressure mechanism or other similar power means, not shown. To provide a convenient way of practicing the invention and to adapt the ram to the use of any size of rod desired,
70 as well as to facilitate the replacement of the rod when it breaks, a sleeve 4 is mounted in the bore 2. This sleeve, as shown, is split axially along one side to allow for expansion and contraction so that it can be inserted and gripped
75 in the bore, and is preferably made with a tapered inner wall conforming in shape to the ram end of the rod 3 which is also preferably tapered, and a cylindrical outer wall which is adapted to fit snugly within the bore with its
80 lower end resting on an annular ledge 5 provided in the lower end of the bore for its reception.

In accordance with my invention to prevent the rod 3 from gripping the sleeve 4 or becoming
85 welded to it in such a way in service that it can
not be removed without considerable difficulty, such as drilling in case the rod breaks, a thin coating or layer 6 of some suitable soft metal, such as copper, is applied either over the outer surface of the lower end of the rod 3 which
90 fits in the ram, or onto the inner surface of the sleeve 4, as illustrated. This coating, which is shown as exaggerated as to thickness in the drawing, is made sufficiently thick to insure the easy removal of the rod, but insufficiently thick
95 to be forced out of the joint or to allow the joint to become loose in service. To prevent its being crumpled and dislodged or destroyed when the rod is inserted in the bore 2, in view of its thinness this coating is made to adhere very
100 tenaciously to the surfaces to which it is applied. To attain this end it may be applied to such surface in various ways, but preferably this is accomplished by electroplating. While as indicated above the thickness of the coating 6 may
105 110

be varied it has been found in practice that the most satisfactory and excellent results may be obtained when thicknesses varying from 3/1000 to 1/32 of an inch are used.

5 Referring to Fig. 2, an embodiment of the invention is shown in which the adapter sleeve 4, shown in Fig. 1, is omitted and in which the lubricating and surface separating coating of soft metal 16, which is employed to facilitate the removal of the rod 13, is applied to such rod which is adapted to fit into the bore 12 provided in the ram 11. While this comprises the simplest application of the invention, as stated above, instead of attaching the layer of lubricating and separating metal 16 to the outer surface of the piston it may be also applied to the surface of the bore 12.

As will be readily appreciated by those skilled in the art, this invention provides a great saving in time and labor in the operation of a forging hammer, as well as saving of the hammer itself, 20 and, as will be also appreciated, it may be applied to other structures where similar problems are encountered and such is contemplated by the appended claims.

25 I claim:

1. In a forging hammer, the combination of a ram provided with a tapered rod-receiving bore, a piston rod having a tapered end tightly wedged in said ram bore, and a thin layer of 30 copper interposed between and adhered to one of the contacting surfaces comprising the tapered faces of said bore and rod.

2. In a forging hammer, the combination of a ram provided with a connection-forming opening, a bushing arranged in said opening and provided interiorly with a tapered rod-receiving bore, a piston rod having a tapered end tightly wedged in said tapered bushing bore, and a thin 35 layer of soft metal interposed between and adhered to one of the tapered contacting faces of said bore and rod.

3. In a forging hammer, the combination of a ram provided with a connection-forming opening, a bushing arranged in said opening and provided interiorly with a tapered rod-receiving bore, a piston rod having a tapered end tightly wedged in said tapered bushing bore, and a thin 80 layer of copper interposed between and adhered to one of the contacting surfaces comprising the tapered faces of said bore and rod.

4. In a forging hammer, the combination of a ram provided with a connection-forming opening, a bushing arranged in said opening and provided interiorly with a rod-receiving bore, a piston rod having an end tightly engaged in said bushing bore, and a thin layer of soft metal 85 tightly adhered to the inner face of said bore.

5. A connection comprising a metal work element of the type subjected to impacts in use and having a bore therein for the reception of a connecting rod, a metal connecting rod rigidly connected in said bore, and a thin coating of soft metal interposed between the contacting surfaces of said rod and bore and tightly adhered to one 90 of such surfaces.

6. A connection comprising a metal work element of the type subjected to impacts in use and having a bore therein for the reception of a connecting rod, a metal connecting rod rigidly engaged in said bore, and a thin coating of soft metal electroplated onto one of the contacting 100 surfaces of said rod and element.

7. For use in engaging a metal connecting rod in a bore in a metal work element of the type subjected to compressive forces in operating a metal sleeve provided with a bore for the reception of a metal connecting rod having a thin 110 face of soft metal electroplated onto the surface of the bore which is adapted to engage such a rod.
